GLUING MECHANISM FOR BOX-MAKING MACHINES

George S. Sillars, Beverly, Mass., assignor to Hoague-Sprague Corporation, Lynn, Mass., a corporation of Massachusetts

Application February 12, 1943, Serial No. 475,666

11 Claims. (Cl. 91—51)

This invention relates to box-making machines, and more particularly to machines of the type disclosed in an application for Letters Patent of the United States Serial No. 410,274, filed September 10, 1941, in the name of C. D. Knowlton, an object of the invention being to provide improved adhesive-applying mechanism particularly adapted for use in machines of the above-mentioned type.

For the purpose in view, the present invention provides an efficient, compact and simple adhesive-applying mechanism in which but a single applying roll is employed the surface of which is of such a character that the roll may be manufactured and reconditioned after wear without special tools.

As herein illustrated and in accordance with one feature of the invention, the single adhesive-applying roll is mounted for rotation about a vertical axis and has its lower end preferably submerged in a receptacle containing adhesive. Co-operating with the adhesive-applying roll is a spreader block which is coextensive with the roll and is arranged yieldingly to engage the roll, the roll-engaging surface of the block being concentric to the axis of the roll. Adjacent to the concentric surface of the block and adjoining the same along a line parallel to the axis of the roll is another surface which diverges from the surface of the applying roll, thereby forming between this surface and the surface of the roll a trapping area or channel in which the adhesive is caught as the roll rotates so that, as the surface of the roll advances toward the trapping channel, the adhesive accumulates, building up in the channel until it reaches the top of the roll. As herein shown, spiral grooves are formed in the surface of the roll which, in co-operation with the spreader block, assist in lifting the adhesive caught in the trapping channel and effect a uniform spreading of the adhesive on the surface of the roll. One of the grooves is relatively wide and has a large angular pitch whereby a large quantity of adhesive is rapidly raised to the top of the roll. The other groove is a comparatively fine V-thread and has a small pitch, this thread serving to lift a small quantity of adhesive but its primary purpose being, in co-operation with the spreader block, to spread the adhesive lifted by the large groove in a uniform film over the surface of the roll. Special means is provided for holding the spreader block in engagement with the roll. This means comprises an arm pivoted for movement to and from the applying roll, upon which the lower end of the

block rests, and an upstanding spindle rising from the arm parallel to the axis of the roll which occupies a groove formed in the block. By swinging the arm away from the roll, the spreader block may be removed from the spindle by lateral movement.

The invention will now be described in detail with reference to the accompanying drawings, in which

- Fig. 1 is a view in front elevation of a portion of a box-making machine with the present invention embodied therein, showing the relation of the improved adhesive-applying mechanism to other parts of the machine;
- Fig. 2 is an angular view of a box-blank of a type operated upon by the machine shown in Fig. 1, the box-blank shown having its corner-laps folded and resting upon the table of the machine;
- Fig. 3 is a plan view on the line III—III of Fig. 4;
- Fig. 4 is a perspective view of the adhesive-applying mechanism of the machine;
- Fig. 5 is a plan view of a portion of the table directly above the end of the adhesive-applying roll;
- Fig. 6 is a fragmentary section of the adhesive-applying roll, showing the relative sizes of the grooves formed in the surface thereof;
- Fig. 7 is a perspective view of a portion of the spreader block, showing the inside surfaces thereof;
- Fig. 8 is a section on the line VIII—VIII of Fig. 4; and
- Fig. 9 is a section on the line IX—IX of Fig. 8.
- The invention is directed specifically to an improvement in the adhesive-applying mechanism of the box-making machine disclosed in application Serial No. 410,274 and therefore only as much of the aforesaid machine as is necessary to afford a clear understanding of the location and function of the adhesive-applying mechanism with respect to the machine as a whole will be herein illustrated and described in detail.
- The apparatus has a hollow base (not shown) from which there rises a tubular column 10 (Fig. 1) having secured across its front near the upper extremity a horizontal bar 16. Fastened to the bar in succession from the outer end thereof are a support A for the box-blanks, a table or guide B upon which a blank is rested as it is operated upon and upon which it is moved from one mechanism to the next, the adhesive-applying mechanism C which is positioned below the table and is adapted to apply adhesive to an end-wing of

the box-blank and its extension, and folding mechanism D which folds the adhesive-coated surface of the end-wing against the corner-laps. The pressure-applying mechanism E is mounted upon the upper end of the hollow column 10 and serves to form a permanent bond between the folded corner-laps and end-wing. In setting up a blank with the aid of this machine, the operator removes a blank S from the support A, preliminarily bends the corner-laps a (Fig. 2) inwardly to a position substantially at right angles to the body of the box, and places the blank with its long dimension in substantially a vertical position with its infolded corner-laps in contact with the table B. The table B has a horizontal portion 12 and an inclined terminal portion 14 which is joined to the horizontal portion by a curved portion 16a. The portions 14 and 16a engage the inwardly partially folded corner-laps and, when the operator presses the blank downwardly and advances it toward the horizontal portion 12, complete the folding thereof (Fig. 2). The blank is then advanced along the horizontal portion 12 of the table B with its end-wing b and extension c projecting downwardly in a position to receive adhesive from the adhesive-applying mechanism C. After receiving a coating of adhesive, the blank is advanced farther along the table to the subsequent mechanisms D and E for the folding and pressing operations which need not be described herein since they are fully illustrated and described in the prior application above referred to.

To permit ready access to the adhesive-applying mechanism for cleaning or inspection, the table B is constructed so that it may be tipped upwardly and backwardly to an out-of-the-way position (Figs. 8 and 9). As shown herein, bosses 18 are fastened to the underside of the table at its rear edge close to the inner side of a pair of uprights 20 which are formed integral with a plate 22 fastened to the bar 16. Alined openings are formed in the bosses 18 and uprights 20 through which there is passed a rod 24 (Fig. 8) having a crank arm 26 formed at one end, for a purpose which will appear hereinafter. By lifting the front edge of the table, it may be tilted upwardly and backwardly about the rod 24. The table is locked in its horizontal position by engagement of a pair of pins 28 (Fig. 9) near the front edge of the table, with the inclined surfaces 30 of a pair of cleats 32 secured to the underside of the table. Since the mechanism is identical at opposite sides of the table, only one side is illustrated herein. As shown, each pin 28 is fastened to a horizontal arm 34 extending forwardly from the uprights 20. The arms 34 serve to support the table in a horizontal position. The inclined surfaces 30 of the cleats are slid under the pins 28 by transverse movement of the table. To accomplish this, the openings in the uprights 20 through which the rod 24 is passed are enlarged to receive eccentrics 36 (Fig. 9) fastened to the rod 24. Thus, by rotation of the crank arm 26 the table may be moved forwardly or rearwardly to latch or unlatch the locking mechanism. It is to be observed that a panel 13 (Fig. 5) is recessed into the table 12 above the adhesive-applying mechanism and is removably fastened in place. This permits access to the adhesive-applying mechanism without lifting the table as a whole, if that is undesirable under operating conditions.

The adhesive-applying mechanism C is fastened to the plate 22, as will subsequently ap- 75

pear, the latter being fastened to the bar 16 by bolt-and-slot connections 38 and 40 so that it may be moved longitudinally of the table B. This permits adjustment of the adhesive-applying mechanism with respect to the folding mechanism and also adjustment for different lengths of box-blanks. As in the prior machine, a receptacle or container 42 (Figs. 4 and 8) for adhesive is provided which may be warmed by an electric heating unit (not shown) attached to the bottom thereof. At the rear of the receptacle is an upward extension 48 which is divided to form arms hooked at 50 over the edge of the plate 22. A pair of screws 52 are threaded through the hooks into contact with the edge of the plate 22 and, by turning down or backing off the screws, the receptacle may be leveled. A tubular extension 54 (Fig. 8) rises from the center of the receptacle in which a shaft 56 is journaled to support an adhesive-applying roll 64 for rotation about a vertical axis. A collar 58 is fastened to the shaft 56 in contact with a bushing 60 which rests on the upper end of the tubular extension 54. The adhesive-applying roll 64 is hollow and a spool 62 occupies the inside upper half of the roll and has transverse ends which engage the inner walls of the roll, thus forming an internal hub through which the upper end of the shaft 56 freely passes. A driving connection between the shaft and the adhesive-applying roll 64 is afforded by a plurality of vertical pins 66 set into the top of the collar 58 and extending into openings formed in the lower transverse end of the spool 62. The upper end of the roll 64 is closed and the upper transverse end of the spool 62 forms a bearing support 70 for the end of the shaft 56. The lower portion of the applying roll surrounds and is spaced from the extension 54 of the receptacle. The adhesive-applying roll 64 is rotated, in the direction indicated by an arrow in each of Figs. 3, 4 and 5, by a pulley 72 (Fig. 8) fastened to the lower end of the shaft 56, the pulley 72 receiving power through a belt 74 driven from a motor 45 mounted on the column 10.

For the purposes of this invention, there is provided a spreader block 76 which, in co-operation with the adhesive-applying roll, traps a quantity of adhesive which is elevated by the continued rotation of the roll in contact with the block to raise the adhesive to the top of the roll and uniformly to spread it on the surface of the roll. The spreader block 76 (Fig. 4), preferably of cast iron, is of substantially the same length as the adhesive-applying roll 64 and is held adjacent to the adhesive-applying roll by a spindle 78, with its lower end resting on a horizontal arm 80 to which the spindle 78 is fixed in an upright position. A half round groove 82 is formed in the rear surface of the block 76 removably to receive the spindle 78. The rear end of the arm 80 rises upwardly and is bent rearwardly at 84. The rear end of the bent-back portion 84 is pivoted upon a pin 86 fixed to one of the divided arms of the upward extension 48. This permits swinging movement of the arm 80, and consequently of the block 76, to and from the surface of the adhesive-applying roll 64. By reason of the half-round groove 82 in the block 76, it is apparent that the block 76 may be removed from the machine by swinging the arm 80 away from the surface of the adhesive-applying roll 64 without having to draw the roll endwise from the spindle 78.

One side of the spreader block 76 (Fig. 7)

is provided with adjoining concave surfaces 86 and 88, the former being of the same radius of curvature as the surface of the adhesive-applying roll 64. A pair of compression springs 90 (Fig. 4) are provided for urging the block 76 toward the surface of the adhesive-applying roll 64. Each spring 90 is supported at one end upon a reduced boss formed at one end of a rod 92 the opposite end of which is reduced in diameter and is threaded at 94 through a post 96 rising from the wall of the container. The free end of each of the springs 90 bears against the spindle 78 and the pressure with which the block 76 bears against the surface of the roll 64 may be regulated by rotation of the screws 94, hand knobs 100 being provided for this purpose. In order to apply the force to the block 76 without causing any twisting of the same one way or the other, a flat bearing plate 98 is interposed between the spindle 78 and the end of each spring 90. The concave surface 86 which lies to the left of the surface 88, as seen in Fig. 7, and toward which the surface of the adhesive-applying roll 64 advances (Figs. 3 and 4) diverges from the surface of the adhesive-applying roll, thereby providing a narrow crevice 102 between the diverging surface of the block 76 and the surface of the adhesive-applying roll from the bottom to the top thereof. This narrow crevice 102, hereinafter called a trapping channel, receives a quantity of adhesive which is carried into it by the advancing surface of the adhesive-applying roll. The adhesive accumulates rapidly therein because of the fact that most of the adhesive on the advancing surface of the adhesive-applying roll is stripped therefrom as it moves beyond the leading edge 104 of the surface 86. As the adhesive accumulates, it is forced upwardly along the trapping channel 102 to the top of the roll where some of it creeps in between the upper end surfaces of the block 76 and the roll and the underside of the table. To dispose of this excess adhesive at the upper end of the roll, a way 106 is formed in the concave surface 86, at the center which, receives the adhesive, the adhesive descending therein by gravity to the bottom of the roll and into the receptacle. The major portion of the excess adhesive is removed by a scraper 108 (Fig. 5) which is fastened to the underside of the removable panel 13 in the table 12. The leading edge 109 of the scraper engages the end of the roll in advance of the block 76. The adhesive scraped from the end of the roll is pushed outwardly along the edge 109 and runs back into the container or drops down into the trapping channel 102.

While a smooth-surfaced adhesive-applying roll will raise some adhesive in the trapping channel 102 between the diverging surface of the block and the surface of the roll, the delivery of adhesive from the bottom to the top of the roll 64, particularly when the machine is first started, would be rather slow. Moreover, the film of adhesive near the top of the roll would be likely to be thin, due to the fact that gravity tends to pull the adhesive down about as fast as the roll lifts it. Accordingly, means is provided on the surface of the adhesive-applying roll which, in co-operation with the block 76, will insure a prompt delivery of adhesive to the top of the roll and will maintain a uniform film on the surface of the roll at all times. As shown herein, this means comprises a spiral groove 110 (Figs. 4 and 6) formed in the surface of the

roll, the groove being relatively coarse, that is, relatively wide and deep, so that it will pick up a large quantity of adhesive. The helix angle of the groove is made quite large so that the adhesive is lifted rapidly. The amount of adhesive carried by the steep-pitched spiral groove 110 is adequate, but, because of the distance between the helices of the groove, the film on the roll consists of alternate heavy and light bands of adhesive. To smooth out the film, a fine V-thread 112 (Fig. 6) having a substantially small angular pitch is formed on the surface of the adhesive-applying roll 64 overlying the coarse spiral groove 110. The roll is made slightly oversize and after the V-thread is cut on the surface of the roll the surface is turned down to provide lands 114 between the helices of the threads. While this fine V-thread 112 carries some adhesive upwardly, its primary function is to spread the adhesive already raised by the coarse groove 110, this being accomplished, in co-operation with the block 76, by the combined scraping and smoothing action of the sharp edges of the lands 114 and the flat surfaces between these edges. The thickness of the film of adhesive may be regulated by rotation of the screws 94 which move the surface of the block 76 to and from the surface of the adhesive-applying roll.

As in the prior machine, the end-wing b and its extension c (Fig. 2) are held against the surface of the adhesive-applying roll 64 as the blank is advanced along the table, by a pressure roll 116 (Fig. 1) adjacent to the applying roll. The pressure roll 116 is freely rotatable about an axis parallel to that of the adhesive-applying roll 64, turning upon a vertical spindle 118 (Fig. 4) the ends of which are fixed in a yoke 120. The yoke is supported by two horizontal rods 122 passing through a post 124 rising upwardly from the front of the receptacle 42. The post 124 is removably secured to the receptacle by a screw 126. The outer ends of the rods 122 are threaded to receive hand nuts 128. Expansion springs 130 are interposed between the post 124 and the yoke 120 about the rods 122. By rotating the hand nuts 128, the position of the pressure roll 116 and the force with which it holds the blank against the adhesive-applying roll may be varied.

The adhesive-applying mechanism of the machine is made ready for use by warming the adhesive until it is of a uniform consistency, starting the machine to cause rotation of the adhesive-applying roll 64, and, finally, by adjusting the block 76 relative to the surface of the roll to cause the adhesive to rise in the trapping channel 102 at a rate fast enough to supply the desired quantity of adhesive to the end-wing and its extension. In setting up a box, a blank is removed from the support A, its corner-laps a are bent inwardly, and it is placed with its inwardly bent corner-laps in contact with the terminal portion of the table. By pressing downwardly, the corner-laps are folded and in this condition the blank is advanced along the horizontal portion of the table with its end-wing and extension projecting downwardly in a position readily to pass between the surface of the adhesive-applying roll 64 and the pressure-applying roll 116. After the adhesive has been applied, further movement of the blank presents it to the folding mechanism and to the pressure-applying mechanism of the machine. These mechanisms are not herein shown and described since they form no part of the present invention. For a full disclosure of the construction and operation

of the folding and pressure-applying mechanisms of the machine reference may be made to the above-mentioned application Serial No. 410,274.

Having described my invention, what I claim as new and desire to secure by Letters Patent of the United States is:

1. In a machine for applying adhesive to box-blanks, a receptacle, an adhesive-applying roll mounted for rotation about a vertical axis with its lower end submerged in the receptacle, a block supported adjacent to the adhesive-applying roll, and means for yieldably urging the block toward the adhesive-applying roll, said block having a roll-engaging surface and another surface lying at that side of said roll-engaging surface toward which the surface of the adhesive-applying roll advances and diverging therefrom, thereby forming a channel between said diverging surface and the surface of the roll.

2. In a machine for applying adhesive to box-blanks, a receptacle, an adhesive-applying roll mounted for rotation about a vertical axis with its lower end submerged in the receptacle, a block movably supported adjacent to the adhesive-applying roll, and means yieldably urging the block toward the adhesive-applying roll, said block having a roll-engaging surface, the edge of said roll-engaging surface toward which the surface of the roll advances serving to strip most of the adhesive from the roll, and another surface lying at that side of said roll-engaging surface toward which the surface of the adhesive-applying roll advances and diverging therefrom, thereby forming a channel between the diverging surface and the surface of the roll to receive the adhesive stripped from the roll, said adhesive accumulating in said channel and being elevated therein by rotation of the adhesive-applying roll.

3. In a machine for applying adhesive to box-blanks, a receptacle, an adhesive-applying roll mounted for rotation about a vertical axis with its lower end submerged in the receptacle, a block movably supported adjacent to the adhesive-applying roll, and means yieldably urging the block toward the adhesive-applying roll, said block having adjoining concave surfaces, one of said surfaces being concentric with the axis of the adhesive-applying roll and having a groove therein extending from top to bottom and the other of said surfaces lying at that side of said one surface toward which the surface of the roll advances and diverging from the surface of the roll, thereby forming a trapping channel between said diverging surface and the surface of the roll in which the adhesive is raised by rotation of the roll to the top thereof, said groove serving to receive the excess adhesive at the top of the roll and to return it to the receptacle.

4. In a machine for applying adhesive to box-blanks, a receptacle, an adhesive-applying roll mounted for rotation about a vertical axis with its lower end submerged in the receptacle, a block, said block having a roll-engaging surface which is concentric with the axis of the adhesive-applying roll and an adjacent surface which is eccentric to the axis of the adhesive-applying roll and diverges from the surface thereof, a groove in the block opposite the concentric roll-engaging surface, and means co-operating with said groove to hold the roll-engaging surface of the block in engagement with the surface of the adhesive-applying roll, said holding means comprising an arm arranged to support the lower end of the block, said arm being mounted for movement

to and from the adhesive-applying roll, and a post fixed to said arm and rising upwardly therefrom in engagement with said groove to hold the block against the surface of the roll whereby upon movement of the arm away from the roll said block may be dismounted from said support by lateral movement.

5. In a machine for applying adhesive to box-blanks, a receptacle, an adhesive-applying roll mounted for rotation about a vertical axis with its lower end submerged in the receptacle, a block having a roll-engaging surface, and means for holding the block yieldably against the surface of the roll, said roll having on its surface means which, in co-operation with the block, quickly elevates a relatively large quantity of adhesive from the bottom to the top thereof, and other means thereon which, in co-operation with the block, effects a spreading of the adhesive on the surface of the roll.

6. In a machine for applying adhesive to box-blanks, a receptacle, an adhesive-applying roll mounted for rotation about a vertical axis with its lower end submerged in the receptacle, a block having a roll-engaging surface, and means for holding the block yieldably against the surface of the roll, said roll having on its surface means for elevating different quantities of adhesive at different rates from the receptacle to the top of the roll, one of said means being adapted, in co-operation with the block, uniformly to spread the adhesive raised by the other of said means.

7. In a machine for applying adhesive to box-blanks, a receptacle, an adhesive-applying roll mounted for rotation about a vertical axis with its lower end submerged in the receptacle, a block having a roll-engaging surface, and means for holding the block yieldably against the surface of the adhesive-applying roll, the surface of said roll having a coarse spiral groove having a relatively large helix angle adapted, in co-operation with the block, rapidly to lift a large quantity of adhesive from the receptacle to the top of the roll and a fine thread of relatively small pitch arranged to lift an additional quantity of adhesive and, in co-operation with the block, to spread the adhesive lifted by the coarse groove.

8. In a machine for applying adhesive to box-blanks, a receptacle, an adhesive-applying roll mounted for rotation about a vertical axis with its lower end submerged in the receptacle, a block having a roll-engaging surface, and means for holding the block yieldably against the surface of the roll, said roll having a spiral groove formed on its surface, the lands between the helices of the spiral groove being wider than the groove, and a fine thread of small pitch traversing said lands a plurality of times between each helix of said groove.

9. In a machine for applying adhesive to box-blanks, a receptacle, an adhesive-applying roll mounted for rotation about a vertical axis with its lower end submerged in the receptacle, a block having a roll-engaging surface, and means for holding the block yieldably against the surface of the roll, said roll having a spiral groove formed on its surface, the lands between the helices of the groove being wider than the groove, and a fine thread of small pitch traversing said lands a plurality of times between each helix of the spiral groove, the lands between each helix of the thread being substantially the same width as the thread.

10. In a machine for applying adhesive to box-

blanks, a receptacle, an adhesive-applying roll mounted for rotation about a vertical axis with its lower end submerged in the receptacle, a block, and means for yieldably holding the block against the surface of the adhesive-applying roll, said block having a surface conforming to a portion of the surface of the roll and a surface diverging therefrom, thereby forming a channel toward which the surface of the roll moves, said roll having on its surface means which, in co-operation with the block, elevates the adhesive in said channel and spreads it uniformly on the surface of the roll.

11. In a machine for applying adhesive to box-blanks, a receptacle, an adhesive-applying roll mounted for rotation about a vertical axis with

its lower end submerged in the receptacle, a block, means for yieldably holding the block against the surface of the adhesive-applying roll, said block having a surface conforming to a portion of the surface of the roll and a surface diverging therefrom, thereby forming a channel toward which the surface of the roll moves, and means associated with said first-named surface of the block to strip the adhesive from the advancing surface of the adhesive-applying roll, thereby to fill the channel with adhesive, said roll having means on its surface which, in co-operation with the block, elevates the adhesive in said channel and effects a uniform spreading of the adhesive on the surface of the roll.

GEORGE S. SILLARS.
